UNITED STATES PATENT OFFICE.

JACK P. PHILLIPS AND NIELS CHRISTIAN AHL, OF PHILADELPHIA, PENNSYLVANIA.

DESIGN FOR A CHALK-SHARPENER.

56,989.

Specification for Design.

Patented Jan. 25, 1921.

Application filed June 18, 1920. Serial No. 390,044. Term of patent 7 years.

To all whom it may concern:

Be it known that we, JACK P. PHILLIPS and NIELS C. AHL, citizens of the United States, and residents of Philadelphia, in the county of Philadelphia and State of Pennsylvania, have invented a new, original, and ornamental Design for a Chalk-Sharpener, of which the following is a specification, reference being had to the accompanying drawing, forming part thereof.

Figure 1 is a view in side elevation of our new design for chalk sharpener.

Fig. 2 is a bottom plan view of the same.

Fig. 3 is a view in transverse section.

We claim:

The ornamental design for a chalk sharpener as shown.

JACK P. PHILLIPS.
NIELS CHRISTIAN AHL.
